[57] CLAIM

The ornamental design for a guiding and locking device for electrical cords, substantially as shown and described.

DESCRIPTION

FIG. 1 is a front perspective view of a guiding and locking device for electrical cords showing our new design with the locking member in the release position; FIG. 2 is a rear perspective view thereof; FIG. 3 is a top view thereof; FIG. 4 is an end view thereof as seen from the right end of FIG. 3;

FIG. 5 is a front perspective view thereof, but with the locking member in the locking position;

FIG. 6 is a rear perspective view thereof with the locking member in the locking position; and

FIG. 7 is a bottom plan view thereof with the locking member in the release position.
